UNITED STATES PATENT OFFICE.

PAUL R. ELLGUTH, OF CHICAGO, ILLINOIS.

STARTER FOR INDUCTION-MOTORS.

1,167,486.

Specification of Letters Patent. Patented Jan. 11, 1916.

Application filed June 13, 1914. Serial No. 844,918.

To all whom it may concern:

Be it known that I, PAUL R. ELLGUTH, citizen of the United States, residing at Chicago, in the county of Cook and State 5 of Illinois, have invented certain new and useful Improvements in Starters for Induction-Motors; and I do hereby declare the following to be a full, clear, and exact description of the invention, such as will enable others skilled in the art to which it 10 appertains to make and use the same.

My invention relates to magnetically actuated starters for electric motors and more particularly to the class of starters used 15 with induction motors requiring a change in the connections for some of their windings during their starting period.

One object of my invention is to provide a magnetically actuated starter adapted to 20 change certain circuit connections when the current flowing through a portion of the motor windings reaches a predetermined volume.

Another object is to provide a simple and 25 positive means for changing the initial slow movement of a magnetically actuated mechanism to a final rapid movement, whereby the switching of the circuit connections is effected with a minimum of arcing at the 30 contacts.

Still another object is to provide a simple gravity actuated means whereby a similarly rapid operation of the switching means in the opposite direction is effected upon a reduction of the current through the starter. 35

Other objects will appear from the following specification and from the drawings accompanying the same.

The starter of my invention is particularly applicable for use in connection with a single phase induction motor having a portion of its stator windings so arranged that the same may produce a phase-splitting effect for the purpose of creating a rotating 45 field of high torque during the starting of the motor, as more fully disclosed in my co-pending application for a patent on an induction motor and starter therefor, filed May 28th, 1914, Serial No. 841415, and is 50 shown in this application in the accompanying drawings, in which—

Figure 1 is a side elevation of the starter of my invention. Fig. 2 is a front elevation of the same. Fig. 3 is a horizontal section 55 through the starter along the line 3—3 of Fig. 1. Fig. 4 is an enlarged detail view

of the auxiliary contact mechanism for temporarily connecting one of the magnet windings of the starter to the circuit. Fig. 5 is a fragmentary side elevation of the starter 60 after the motor has been brought up to speed. Fig. 6 is a diagrammatic view of the starter of my invention as connected to the circuits of an induction motor of the type shown in the co-pending patent application heretofore mentioned. 65

In the embodiment of the drawings, the starter of my invention consists of an electromagnet having two windings, the said magnet being mounted upon a base 1 of slate 70 or other insulating material, which base is preferably the front of a rheostat containing the resistance 33. The magnet preferably consists of an iron frame 3 supporting an insulating tube 4 having a square bore. 75 Slidably positioned in this tube is a laminated core 5 composed of strips of soft iron riveted together, this core having an elongated slot 6 near its lower end. Mounted upon the forward portion 7 of the magnet 80 frame are trunnions 8 for an axis 9, which axis serves as a pivot for a rocking bar 10. The said rocking bar has at its opposite ends contact members 11 and 12, each composed of thin strips of copper or bronze, 85 and each suitably insulated from the rocking bar 10, each of which contact members is adapted to bridge across a pair of metal contacts disposed in proximity to the said bridging contact. Thus the upper bridging contact 11 is adapted when the rocking bar 90 is in one extreme of its normal position (as in Fig. 5) to contact with and bridge across terminals 13 and 14, the said terminals being mounted, respectively, upon slate pillars 15 and 16 carried by the base 1. Likewise, the lower bridging contact 12 is adapted, when the starter is in its idle position, (as shown in Fig. 1) to bridge across a pair of terminals 17 and 18 supported, 95 respectively, by slate posts 19, the said posts also being mounted upon the base 1.

Extending transversely through the perforation 6 in the lower end of the laminated core 5 is a pin 20 which serves as a pivotal 105 connection for a pair of links 21 and 22, the former of which is pivotally connected to an extension 23 at the lower end of the rocking arm 10. The companion link 22 is similarly pivotally connected to an extension 24 110 of the magnet frame 7, which extension also has a stop 25 adapted to limit the up-

ward movement of the link 22. The pin 20 is preferably considerably smaller in diameter than the width of the perforation 6, thereby permitting the pin 20 to move laterally with respect to the axis of the magnet without interfering with the free vertical motion of the laminated core 5. Secured to the upper end of the said core 5 is a rod 26 carrying a transverse member 27 having a tongue 28 pivoted at one edge of the latter, this tongue being normally held in a position substantially at right angles to the axis of the magnet by a spring 29 also carried by the rod 26. The transverse member 27, the spring 29 and a spring stop 30 disposed at the other side of the tongue 28 are all suitably insulated from the rod 26, the member 27 being connected by a flexible wire 31 to the terminal 13, which is one of the terminals of a source of single phase current when the starter is in use.

The companion terminal 14 is connected to the said terminal 13 through a wire 32 and a resistance 33, which resistance is short-circuited when the upper bridging contact 11 bridges across the said terminals 13 and 14. The terminal 14 is also connected by a wire 34 to the multiple-grouped windings 35 and 36, which groups of windings are in series with each other, as shown in Fig. 6. Connected to the juncture of the said groups of windings 35 and 36 to form a "star connection" therewith are the series-connected windings 37 (the said windings 35, 36 and 37 being suitably disposed upon the stator of the motor), the other end of which series of windings 37 is connected by a wire 38 to the terminal 18 mounted upon one of the lower posts 19. The companion terminal 17 is permanently connected by a wire 39 to the upper terminal 13, thereby connecting the said terminal 17 continuously to one terminal 40 of the source of single phase current. The other terminal 41 of this circuit 42 is connected by a wire 42 to the free end of the multiple-grouped windings 36 and through a wire 43 to one end of each of the magnet or solenoid windings 44 and 45, which windings are upon the square insulating tube 4. The other end of the magnet winding 44 is connected by wires 46 and 34 to the other terminal of the multiple-grouped windings 35 of the stator and to the contact terminal 14 carried by one of the upper posts of the starter. The upper terminal of the magnet winding 45 is connected by a winding 47 to a rigid contact 48 positioned upon the base 1 in the path of the pivoted tongue 28.

When the motor is idle, the parts will be in the relative positions shown in Fig. 6, with the lower bridging contact 12 connecting the contacts 17 and 18, thereby connecting the line terminal 40 to the series-joined windings 37 of the stator and through the

resistance 33 to the multiple-joined windings 35, while the other line terminal 41 is connected directly to the multiple-grouped windings 36. The result will be the production of a split-phase current in the respective starter windings when the current is turned on, thereby producing substantially the effect of a three-phase current for starting the motor. The magnet winding 44 being in shunt with the free ends of the two groups of multiple-connected stator windings 35 and 36, and the resistance of the stator windings being quite low, the said magnet winding will at first receive only a very small amount of current. However, as the motor increases in speed, the inductive effect of the rotor windings upon the stator windings will decrease the flow of current through the said stator windings 35 and 36, thereby causing a larger proportion of the line current to flow through the magnet winding 44. Consequently, the effective strength of this magnet winding and its resulting pull upon the core 5 will gradually increase as the motor approximates its normal speed, hence the said magnet will raise its core more and more until the tongue 28 contacts with the fixed terminal 48, thereby also connecting the auxiliary magnet winding 45 to the circuit in multiple with the winding 44. When this occurs, the effective pull of the magnet will be suddenly and greatly increased, thereby giving an additional and rapid upward motion to the core 5 and causing the tongue 28 to be drawn upward beyond and out of contact with the terminal 48 co-acting therewith. Owing to the pivotal mounting of the tongue 28, this will be free to swing out of alignment with the member 27 supporting the same (as shown in Fig. 4) and as soon as the tip of the tongue has passed the tip of the terminal 48, the spring 29 will again force the said tongue into alignment with the supporting member 27, thereby causing a rapid breaking of the contact at the tip of the tongue so as to avoid any serious arcing at this point.

When the magnet core is being gradually drawn up into the magnet while the motor is gaining in speed, this will have no effect upon the rocking bar 10 and the contacts carried thereby until the lower end of the slot 6 is raised sufficiently to engage the pin 20, whereupon a further raising of the core 5 will raise the juncture of the links 21 and 22 so as to carry them toward the position shown in Fig. 5. By suitably proportioning the length of the slot 6 and the distances between the tongue 28 and the contact terminal 48, I cause the auxiliary magnet winding closed through the said tongue and contact to effect the sudden final movement of the core after the pin 20 has already been engaged by, or at about the moment

when the pin 20 is engaged with, the lower end of the slot 6, thereby causing the jointed links 21 and 22 to effect a sudden tilting of the rocking bar 10. Consequently, the lower bridging contact 12 will be quickly moved out of contact with the lower post terminals 17 and 18, while the upper bridging contact 11 will quickly be forced into engagement with the terminals 13 and 14. 10 When this occurs, the series-connected stator windings 37 will be disconnected entirely from the source of current and the resistance 33 will be short-circuited by the bridging contact 11, thereby connecting the two groups of multiple-joined stator windings 35 and 36 in series with each other across the line terminals 40 and 41 so that the motor will operate after the usual fashion of single-phase induction motors. When the 20 motor is thus running, the magnet winding 44 will remain continuously in shunt with the active stator windings, thereby maintaining the normal connections to the circuit. When the line current is disconnected from the motor, as by opening a switch 49, the 25 flow of current through the double wound solenoid will cease, thereby permitting gravity to retract the core 5. In doing so, the core will be free to move for a considerable distance before the upper end of the slot 6 engages the pin 20; consequently this core will have attained a considerable momentum, thereby enabling the core to overcome any tendency of the links 21 and 22 30 to bind or remain in the position of Fig. 5. To further overcome any such tendency of the moving parts to stick or bind, I preferably interpose a compression spring 50 between the upper end of the rocker arm 10 and the magnet frame 3.

While I preferably use a rocking arm for carrying the two bridging contacts (which coat with the terminals supported by the posts to form switches) and preferably interpose a pair of jointed links between this rocker arm and the actuating core of the magnet, I do not wish to be limited to this construction, as other transmission means might be used for imparting a relative motion to the said bridging contacts. Thus the diagrammatic view of Fig. 6 shows that the two bridging contacts might be moved vertically by mounting both of them slidingly upon the core 5 and providing the latter 45 with a pair of pins 51 adapted to engage the said contacts when the core has been raised to a predetermined extent, due provision being made for insulation which is not shown in the diagram of Fig. 6. So, also, I do 50 not wish to be limited to the particular arrangement of pivoted tongue and spring construction as used for making the auxiliary and temporary contact during a portion of the stroke of the armature core, it 55 being obvious that these and other details of

construction herein disclosed might be varied considerably without departing from the spirit of the appended claims.

I claim as new and desire to secure by Letters Patent:

1. A motor and starter combination, including an electric motor having an auxiliary starting winding, a movable member interposed in and forming part of the current supply circuit for the said auxiliary winding; a pivoted lever carrying the said movable member, a solenoid in circuit with the main windings of the motor; a support and a sliding core for the said solenoid, and a pair of jointed links connected at their free ends respectively to the said pivoted lever and the said support, the common pivot of the said jointed links being interposed in the path of a portion of the said core, whereby the movement of the said core is adapted to move the said links with respect to each other. 70

2. A motor and starter combination, including an electric motor having main and auxiliary windings, a resistance adapted to be inserted in series with the said main windings, a solenoid having a winding continuously in shunt with the said main windings, a switch adapted to connect the auxiliary winding to one terminal of the operating circuit, a second switch adapted to short-circuit the said resistance, a movable core for the solenoid, and transmission mechanism connecting the said core with both of the said switches for simultaneously operating the said switches by the movement of the said core. 90

3. A motor and starter combination, including an electric motor having main and auxiliary windings, a pivoted switch controlling the said auxiliary windings, and magnetically actuated apparatus for actuating the said switch; the said mechanism comprising a solenoid winding continuously connected to the circuit, a movable core for the said solenoid, and connections between the said core and the said lever-actuated switch for causing the movement of the core to actuate the said switch. 95

4. A motor and starter combination, including an electric motor having main windings and auxiliary windings, a movable switching member controlling the said auxiliary windings, a solenoid subject to the flow of current in the main windings of the motor, a core for the solenoid, the said core having a slotted end; and a link connecting the said movable switching member with the slotted end of the said core, the slot in the latter affording an engagement between the core and the said link after the core has been moved a predetermined distance. 110

5. A motor and starter combination, including an electric motor having main and auxiliary windings, a resistance adapted to 120

125

130

be inserted in series with the former of the said windings, a switch member adapted to short circuit the said resistance, another switch member controlling the circuit connection to the latter of the said windings; a rocking lever carrying the said switching members at its opposite ends, a solenoid having a winding in shunt with the former of the said motor windings; a core for the said solenoid, and connections between the said core and the said rocking lever for transmitting the motion of the core to the lever to actuate the said switching members.

6. A motor and starter combination, including an electric motor having a plurality of windings, a movable switching member controlling one of the said windings, a solenoid having a pair of windings thereon, one thereof continuously connected to the motor circuit; a movable core for the solenoid, connections between the core and the switching member for transmitting the motion of the core to the said switching member; and a pair of contacts controlling the circuit connections to the other of the said solenoid windings, one of said contacts being carried by the said core.

7. A motor and starter combination, including an electric motor having a plurality of windings, a movable switching member controlling one of the said windings; a solenoid having a pair of windings thereon, one thereof continuously connected to the motor circuit; a movable core for the solenoid; connections between the core and the switching member for transmitting the motion of the core to the said switching member; and a pair of contacts controlling the circuit connections to the other of the said solenoid windings, the said contacts being adapted to contact with each other during a portion of the travel of the said core, the contact portion of one of the said contacts being pivotally mounted.

45 8. A motor and starter combination including an electric motor having main and auxiliary windings, a movable switching member controlling the said auxiliary windings, a solenoid subject to the flow of current in the main windings of the motor, a core for the solenoid, connections between the core and the switching member whereby the movement of the core will actuate the switching member, and means associated with said connections for preventing the core from actuating the switching member before the core has been moved a predetermined distance.

9. A motor and starter combination including an electric motor having a plurality of windings, a movable switching member controlling one of said windings; a solenoid having a pair of windings thereon, one thereof continuously connected to the motor circuit; and means actuated by the flow of

current through the said continuously connected solenoid winding for momentarily connecting the other of said solenoid windings to the motor circuit and for thereafter operating the said switching member.

10. A motor and starter combination including an electric motor having a plurality of windings, a movable switching member controlling one of said windings; a solenoid having a winding continuously in the motor circuit; means actuated by the flow of current through said solenoid winding for moving said switching member, and means associated with the aforesaid means for accelerating the speed at which the latter moves the switching member.

11. A motor and starter combination, including an electric motor having a plurality of windings, a movable switching member controlling one of said windings, a solenoid subject to the flow of current in one of the windings of the motor; a core for the solenoid connected to said switching member and actuated by the flow of current through said solenoid winding to operate the switching member, said core being gravity-retracted; and means associated with said core and the connections of the latter to the switching member for preventing said core from actuating said connections until the core has dropped for a predetermined distance, whereby the momentum acquired by the core while falling through the said distance will cause the same to move the said switching member with considerable speed.

12. A motor and starter combination, including an electric motor, a starting resistance therefor, a movable switching member adapted to short-circuit said resistance; a solenoid having a pair of windings, one thereof continuously subject to the flow of current through the motor, the other thereof adapted to be connected in shunt with the former of said solenoid windings; a core for said solenoid; connections between said core and the switching member for causing the movement of the core to actuate said member to short-circuit the said resistance; and means associated with said core and momentarily operated during the movement of the core under the influence of the first named solenoid winding, for connecting the other of the solenoid windings in shunt with the former, thereby causing the joint action of said windings on the core to accelerate the movement of the core and the speed at which the latter actuates the switching member.

13. A motor and starter combination including an electric motor having main and auxiliary windings, a resistance adapted to be inserted in series with the said main windings, a solenoid having a winding continuously in shunt with the said main windings, a switch adapted to connect the auxiliary

- winding to one terminal of the operating circuit, a second switch adapted to short-circuit the said resistance, a movable core for the solenoid, transmission mechanism 5 connecting the said core with both of the said switches for simultaneously operating the said switches by the movement of the said core: and means associated with said core and operated at a predetermined point 10 in the movement thereof for accelerating the movement of said core, thereby increasing the speed at which the core operates both of said switches.
14. A motor and starter combination, including an electric motor, a starting resist-
- ance therefor, a solenoid subject to the flow of current through the motor, mechanism operated by the solenoid for short-circuiting the starting resistance, and means associated with said mechanism and said solenoid 20 for momentarily accelerating the speed at which the solenoid operates the said mechanism.
15. In testimony whereof I have signed my name in presence of two subscribing witnesses.

PAUL R. ELLGUTH.
